(57) **CLAIM**

The ornamental design for a lawn game component, as shown and described.

DESCRIPTION

FIG. 1 is an isometric view of a lawn game component showing our new design;

FIG. 2 is a side view thereof, as taken from the left side of FIG. 1;

FIG. 3 is a side view thereof, as taken from the right side of FIG. 1;

FIG. 4 is a top view thereof;

FIG. 5 is a bottom view thereof;

FIG. 6 is a front end view thereof; and,

FIG. 7 is a rear end view thereof.

The broken lines in FIGS. 1, 2, 3, 4, 6 and 7 are for illustrative purposes only and form no part of the claimed design.

1 Claim, 5 Drawing Sheets
